(57) **CLAIM**

The ornamental design for an animal trap, as shown and described.

DESCRIPTION

FIG. 1 is a front elevation view of an animal trap showing the new design and which is enlarged in comparison to the other views;

FIG. 2 is a front, top, right side perspective view thereof;

FIG. 3 is a rear, top, left side perspective view thereof in an alternate configuration wherein the trap is closed;

FIG. 4 is a right side elevation view thereof in the initial configuration, wherein the left side elevation view is the same;

FIG. 5 is a top plan view thereof in the initial configuration;

FIG. 6 is a bottom plan view thereof in the alternate configuration; and,

FIG. 7 is a front, top, right side perspective view thereof in the alternate configuration.
